UNITED STATES PATENT OFFICE.

DAVID HEPHER, OF CARROLLTON, MISSOURI.

DESIGN FOR A HOE.

SPECIFICATION forming part of Design No. 25,918, dated August 11, 1896.

Application filed June 8, 1896. Serial No. 594,799. Term of patent 7 years.

To all whom it may concern:

Be it known that I, DAVID HEPHER, of Carrollton, Carroll county, Missouri, have produced a new and original Design for a Hoe, of which the following is a full, clear, and exact description, reference being had to the accompanying drawing, forming a part hereof.

My invention relates to weed destroying or extracting implements; and my object is to produce an agricultural implement of this class of a new design, the leading feature of which consists in a horizontal plate sharpened at its opposite sides and in upwardly-projecting attenuated end plates provided with sharpened margins, which sharpened surfaces occur at the upper and inner sides of said parts, respectively. Said design is illustrated by the accompanying drawing, which shows in perspective my implement and also shows a handle, or a connection for an ordinary long wooden handle, of no importance as regards the form of the cutting portion of the implement.

Referring to said drawing in detail, 1 designates an elongated horizontal plate, and 2 designates upwardly-projecting end portions of the same, which end portions are attenuated or diminished in width toward their upper ends, as at 3. The upper surface of the plate 1 at its front and rear margins or sides is beveled, as shown, to produce sharp cutting edges, and the end portions 2 at their inner sides are also beveled, as shown at 5, to produce cutting margins. 25 30 35

Having thus described the invention, what I claim as new, and desire to secure by Letters Patent, is—

The design for a hoe substantially as herein shown and described. 40

In testimony whereof I affix my signature in presence of two witnesses.

DAVID HEPHER.
